FRED D. WILSON, OF HARVEY, ILLINOIS, ASSIGNOR TO AUSTIN MANUFACTURING CO.,
OF CHICAGO, ILLINOIS, A CORPORATION OF ILLINOIS.

ROAD-SURFACE RESMOOTHER.

Application filed February 23, 1924. Serial No. 694,527.

This invention is a machine, specifically a roller mechanism, for removing the irregular ruts and corrugations which appear in the use of conventional paved streets or highways, and particularly to asphalt pavements which, as is well understood in the art, develop waves or cross-ridges caused by heavy traffic—this particularly in warm weather when the material is in a most pliable condition and tends to creep ahead and be unevenly compressed by the passing vehicle wheels.

The object of this invention is to provide a machine equipped with a plurality of rollers following one after the other which under normal road surface conditions will apply to the road surface a part of the total load of the roller mechanism in proportion to the number of rollers; but which will, when a particularly irregular or hard ridge in the road surface is encountered, apply a very much larger percentage of the total weight of the machine to that particular obstruction, thereby reducing it to a level in conformity with other parts of the road surface.

The further object of the invention is to provide such a machine with mechanism enabling it to travel in curved lines as well as in straight lines. The further object is to selectively provide at whichever may for the moment be the forward end of the machine a roughened roller or other tool adapted to work into the rough ridges on the road surface preparatory to their being engaged by the smooth surface rollers which follow said special roller.

The invention consists in mechanism for attaining the foregoing and other objects; which can be comparatively easily and cheaply made; which is satisfactory in use and is not readily liable to get out of order.

More particularly, the invention consists in numerous features and details of construction which will be hereafter more fully set forth in the specification and claims.

Referring to the drawings in which like numerals designate the same parts throughout the several views:

Figure 1 is a plan view of mechanism illustrating this invention in its preferred form, adjusted for straight forward and back movement in treating a road surface.

Figure 2 is a side view partially in sec-

tion taken on the irregular line 2 of Figure 1.

Figure 3 is a changed position view of the parts of Figure 1 showing the machine arranged to travel in a curve.

Figure 4 is a transverse end view on the irregular line 4—4 of Figure 1.

Figure 5 is a similar view on the irregular line 5—5 of Figure 1.

In the particular embodiment of the invention shown in the drawings, seven road surface engaging rollers are provided bearing the numerals 11 to 17, inclusive; but a greater or less number of such rollers may be used without departing from the invention. Above these rollers is a rigid, in the particular case here illustrated, a rectangular frame 18, to which the yoke 20 of the middle roller 14 is rigidly attached by any suitable means; as, for instance, the rivets 22 passing into the bottoms of separated, depending lugs 24 formed in the central, transverse cross-member 26 (clearly shown in Fig. 4) of the main frame 18.

Above each of the other rollers 11—13 and 15—17 is a cross member 28 rigidly secured to the sides of frame 18 by any suitable means as, for instance, bolts 30. Each of these cross members 28 differs from cross-member 26 in the provision of a depending central bearing 32 journaling a vertical shaft or king pin 34, rigidly secured by any suitable means, as a pin 36 to the yoke 38 belonging to the roller which is under the particular cross-member 28 in question. The under sides of the outer ends of all the cross-members 28 are equipped with suitably rigidly attached bearing blocks 40 against which the upper bearing surfaces 42 of the adjacent yoke 38 slide as the adjacent roller is turned on the king pin 34 in the manner hereinafter described. Removable bolts 44 are provided for insertion through a given cross-member 28, block 40 and into adjacent yoke 38, as shown in Figures 1 and 5 to temporarily rigidly secure all of the rollers 1—13 and 15—17 parallel to each other for actual road working in straight lines lengthwise of the machine.

When it is desired to have the machine work on a curve or turn a corner, the bolts 44 are removed, thereby allowing the device to assume the position shown in Figure 3.

In order to automatically adjust all of the rollers to the angular position shown in Figure 3, required for working on a curve or traveling around corners, the yokes of 5 rollers 11 and 12 are connected together by a connecting rod 46, lying at one side of the central axis of the machine; the yokes of rollers 12 and 13 are connected by a similarly disposed connecting rod 48; the yokes 10 of rollers 13 and 15 are connected together by a diagonally disposed connecting rod 50, which crosses the center line of the machine; yokes 38 of rollers 15 and 16 are connected by a link 52, lying on the opposite side of 15 the center of the machine from links 46 and 48; and, finally, the yokes of rollers 16 and 17 are attached together by a connecting rod 54 in substantial alignment with 20 and on the same side of the machine as connecting rod 52. For strength and efficiency of action, the connecting rods described are provided in duplicate; the second set being designated 46^a to 54^a, respectively; but only one of these sets is actually required. Piv- 25 otally attached to the yoke 36 of roller 11 is a push-pull member 56 adapted to be engaged by any suitable mechanical or animal source of power capable of pushing or pulling, as the case may be, the entire ma- 30 chine over the road. The roller 17 is equipped with a corresponding push-pull member 58. The result of the connecting rod and push-pull device construction, just described, is that when the bolts 44 are re- 35 moved and a given push-pull part, as 58, is rotated from the position of Figure 1 to that of Figure 3, all of the rollers in the machine except the central one 14 are turned on their king pins 34 to the position shown 40 in Figure 3, and that it is entirely obvious that rocking the member 58 in the opposite direction will correspondingly oppositely dispose the various rollers of the machine, the result of this construction being that the 45 machine can be, within reasonable limits, positioned as desired to move either in a perfectly straight line lengthwise of the machine as it will when the parts are in the position of Figure 1, or to move in the arc 50 of a circle, as it will when the parts are in the position of Figure 3.

In the drawings, end rollers 11 and 17 are shown as provided with corrugated surfaces which in practice more readily work 55 into the rough ridges on the road surface 60 traversed by the machine than do the smooth, symmetrical surfaces of the rollers 11-16, inclusive; as, obviously, when the corrugated roller is provided, it is only wanted for use at the head of the machine in the direction in which the machine is 60 going. The shafts 62 of these front and rear rollers are mounted upon conventional eccentrics 64, manipulated by suitable mechanism, such as handle 66, so that the follow-

ing or rear end corrugated roller can be elevated off from the ground by manipulation of the eccentric and thus thrown out of action where it cannot re-roughen the road surface 60 which has been smoothed by the 70 rollers 12-16 which just preceded that particular corrugated roller along the road surface.

When the machine thus constructed and manipulated is placed on a roughened road 75 surface 60 and by pushing or pulling on the members 56 or 58 moved over the road surface, the weight of the entire machine, say 32,000 pounds, will, if the road surface 60 is fairly smooth, be distributed substantially 80 equally over the six rollers (one corrugated roller being raised) which engage the road surface; but, if an unusually high and resi- 85 stant roughness in the road surface 60 is encountered, it will receive substantially half of the weight of the machine when the front 90 roller 11 or 17, as the case may be, strikes it and bears upon it, thereby momentarily lifting the next four rollers off from the ground and, if the road obstruction 95 continues resistant long enough, until it is reached by the center roller 14, which may momentarily receive the entire weight of the machine, all of the rollers, except roller 14, being momentarily suspended in the air by 100 means of roller 14 bearing on the road ob- struction and the co-operating rigid frame 18 which carries the other rollers from roller 14.

This described result is obtainable because 100 of the fact that the complete frame 18 is, by the use of the box-shaped cross-members 26 and 28, made sufficiently rigid so that it does not flex downward when the entire load is carried by roller 14 to thereby allow 105 the remaining rollers to touch the road sur- face.

The rollers 11 and 17 may be made with smooth surfaces like the remaining rollers should the constructor so desire, without de- 110 parting from this invention.

The upper end of each king pin 34 is provided with a conventional spring 66 which serves to hold the adjacent yoke 38 in good rotating position on the bottom of 115 the adjacent member 32.

The rods 46-54 are so proportioned and their pivot pins 70 on the yokes 28 are so placed that when the rollers are in the po- 120 sition of Figure 3, imaginary line exten- sions of the axis of rotation of the various rollers intersect at a common center (below Fig. 3) remote from the machine about which the machine as a whole travels, and that in intermediate, angular positions of 125 the rollers between those of Figures 1 and 3, the said axial lines continue to intersect each other at other common centers located be- 130 tween the point above described and a point at infinity, i. e., the intersecting center of 135

said parallel axial lines in the position of Figure 1.

Having thus described my invention, what I claim as new and desire to secure by Letters Patent is:

1. In mechanism of the class described, a multiplicity of tandem horizontally disposed road rollers, a frame sustaining said rollers, sufficiently rigid with reference to each other so that when a central roller passes over a road obstruction, the other rollers are sustained off the road thereby throwing the weight of the entire machine on the one roller, means pivoting certain of the rollers on vertical axes and a series of diagonally disposed connecting rods between said pivoted rollers so arranged that manually rock-

ing one pivoted roller on its vertical axis simultaneously so rocks all the pivoted rollers that the machine can move in a curve. 20

2. In mechanism of the class described, a frame supporting a multiplicity of tandem horizontally disposed road rollers, means pivoting certain of the rollers on vertical axes, and a series of diagonally disposed connecting rods between said pivoted rollers so arranged that manually rocking one pivoted roller on its vertical axis simultaneously so rocks all of said pivoted rollers that the machine can move in a curve. 25 30

In witness whereof, I have hereunto subscribed my name.

FRED D. WILSON.
